UNITED STATES PATENT OFFICE.

FRANK H. CRUMP, OF LOS ANGELES, CALIFORNIA.

TEMPORARY BINDER.

Application filed July 13, 1926. Serial No. 122,236.

My invention relates to temporary binders for magazines, catalogues and similar publications having flexible covers, and a purpose of my invention is the provision of a temporary binder which is capable of securely holding magazines and similar publications of various thicknesses and forms of binding such as center or side wire stitch, sewed or otherwise held together.

It is also a purpose of my invention to provide a temporary binder in which the cover thereof is made without reference to the magazine retaining means, and the latter formed separately and subsequently secured to the cover.

A further purpose of my invention is the provision of a temporary binder in which the magazine retaining means is adapted for use upon any size cover, thereby simplifying the construction and reducing the cost of manufacture of the binder as a whole.

I will describe only one form of temporary binder embodying my invention, and will then point out the novel features thereof in claims.

In the drawings:

Figure 1 is a view showing in perspective one form of temporary binder embodying my invention;

Figure 2 is a detail perspective view of one of the holding brackets embodied in the binder shown in Figure 1;

Figure 3 is a central longitudinal sectional view of the binder shown in Figure 1;

Figures 4 and 5 are sectional views taken on the lines 4-4 and 5-5 of Figure 3;

Figure 6 is a view similar to Figure 5, showing another adaptation of my invention.

Similar reference characters refer to similar parts in each of the several views.

Referring specifically to the drawings, my invention in its present embodiment as shown in Figure 1 comprises a cover including a front section 15 and a back section 16 hingedly connected to a central portion 17 by a binding material 18, this material being also employed to retain a back member 19 formed of wood or other suitable material to the back portion 17.

Adjacent to the ends of the back member 19 are secured by means of screws or other suitable fastening members a pair of holding brackets H, each of which, as clearly shown in Figure 2, is constructed from a strip of metal or other suitable material bent

to provide a flat base portion 20 secured to the back member 19 and an upstanding portion 21 of rectangular outline. The inner wall of the portion 21 is formed with perforations 22, while the outer wall thereof operates as an abutment for limiting the longitudinal movement of a fastening member F inserted into the perforations 22, as illustrated in Figure 1. In this figure the arrangement of the holding brackets H is disclosed and it will be noted that the perforated walls of the portions 21 are in confronting relation with respect to each other in order that the perforations thereof may receive the opposite ends of the fastening member F.

The fastening member F comprises in the present instance a single length of resilient wire of a length exceeding the distance between the perforated walls of the portions 21 of the brackets H so that in applying the member to the brackets it is necessary to bow the member, as indicated in dot and dash lines in Figure 3 in order to place the ends 80 of the member within the perforations 22.

As shown in Figure 1 the back member 19 is provided with three clamping brackets C, all of which are substantially of identical construction so that a description of one will suffice for all. Each bracket is formed of light weight spring steel or other suitable material which is more or less flexible to allow for easy spreading thereof to permit the insertion of a magazine therein and yet stiff enough to act as a clamp to restrain the magazine against turning movement beneath the fastening member F. Each clamping bracket is made from a single piece of spring steel or the like, and is constructed to provide a flat base 23 which is secured to the back member 19. Upstanding from the flat base are a pair of jaws 24 curved inwardly toward their free edges and then flared outwardly at their free edges in order to facilitate the insertion of magazines within the brackets, as will be understood. The three brackets are arranged in longitudinal alignment on the back member, with the two end brackets secured to the back member by having their flat portions 23 interposed between the back member and the flat portions 20 of the brackets H. The intermediate bracket C is directly secured to the back member by screws 25.

In practice, the magazine may be secured within the binder by first removing the fas-

tening member F. This may be accomplished by flexing the member to the position shown in dot and dash lines in Figure 3, whereby its ends will be removed from the perforations 22 of the brackets H. With the fastening member F removed the bound portion of the magazine can be inserted into the several clamping brackets C in the manner clearly illustrated in Figure 4, whereupon by opening the magazine the fastening member can be reapplied so that its ends are again disposed within the perforations of the brackets while the intermediate portion extends between the leaves of the magazine. If the magazine is relatively thick, as illustrated in Figure 4, the fastening member is extended into the uppermost openings of the brackets H, and in this position of the fastening member it is disposed below the lipped edges of the clamping brackets so as to retain the magazine within the clamping brackets and to cause the latter to function in restraining the magazine against turning movement beneath the fastening member, whereby the magazine is securely retained within the cover while the leaves thereof are free to be turned.

If the magazine is a relatively thin one, the fastening member is extended into one of the lowermost perforations 22 of the brackets H, as illustrated in Figure 5, while if a plurality of relatively thin magazines are secured within the binder a plurality of fastening members F are employed in the manner illustrated in Figure 6. It is to be noted that the perforations 22 of the brackets H are arranged to form a vertical series and a horizontal series. The vertical series of perforations are designed for holding single magazines of various thicknesses and various binding means, while the horizontal series are designed to provide for holding a plurality of relatively thin magazines of the same issues but different dates. It is also possible to insert two relatively light fastening members F in one perforation which will provide for six issues of the same magazine.

A binder constructed in accordance with my invention is very simple in construction, yet capable of securely holding a magazine of any size or thickness and any form of binding in a manner to allow all of the reading matter thereof to be visible at all times. The cost of manufacture is greatly reduced as compared to other binders, as any sized binder may be made by simply sawing the back members to the proper length and constructing the covers as described, the holding and clamping members being readily attachable to the back member and interchangeable with respect to a plurality of covers.

Although I have herein shown and described only one form of temporary binder

embodiment of my invention, it is to be understood that various changes and modifications may be made therein without departing from the spirit of the invention and the scope and spirit of the appended claims.

70

I claim:

1. A temporary binder comprising a cover having a back member, a plurality of longitudinally aligned brackets secured to the back member and having flexible portions between which the bound portion of a magazine is adapted to be received and flexible fastening members disposed within and extending from one bracket to the other, said members being detachably secured within the brackets and adapted to extend between the leaves of a magazine in a manner to retain the latter within the brackets and to cause the brackets to restrain the magazine against turning movement between the fastening members.

2. In a temporary binder, a cover having a back member, holding brackets secured to the back member and having confronting walls constructed to provide a series of vertical perforations and a series of horizontal perforations, elongated resilient fastening members adapted to be flexed to permit the insertion of their ends into the perforations of the brackets and to return to their original form after insertion into the perforations, said brackets being formed with walls to limit the longitudinal movement of the fastening members within the brackets, and adjustable brackets secured to the back member and having bendable portions disposed to embrace magazines secured to the back member by said fastening members in a manner to restrain the magazines against turning movement beneath the fastening members.

3. A temporary binder comprising a cover having a back member, brackets secured to the back member and perforated, a resilient fastening member adapted to be flexed for insertion into the perforations of the brackets and adapted to extend from one bracket to the other and between the leaves of a magazine to retain the latter on the back member, and other brackets secured to the back member between the first brackets and having bendable portions at opposite sides of the fastening member adapted to be bent to accommodate and embrace the bound portions of magazines of respectively different thicknesses, to thereby restrain the magazine against turning movement beneath the fastening member.

4. The binder as embodied in claim 3 wherein the bendable portions comprise a pair of spaced jaws inclined upwardly towards each other to provide fulcrums at their upper ends for the leaves of a magazine when open and co-acting with the resilient clamping member engaging the magazine.

125

130

at its binding to prevent turning of the magazine in and its removal from the bracket.

5. The binder as embodied in claim 3 wherein the bendable portions comprise a pair of spaced jaws inclined upwardly towards each other with their free ends flared outwardly from each other to facilitate the insertion of a magazine between the jaws and forming a rounded support for the leaves of the magazine when open.

6. A temporary binder comprising a cover having a back member, brackets secured to the back member and having vertical 15 fronting walls constructed to provide a series of horizontal perforations and a centrally disposed series of vertical perforations above the horizontal series, resilient fastening members adapted to be flexed to 20 permit the insertion of their ends into the

perforations of the brackets and to return to their original form after insertion into the perforations, said brackets being formed with walls to limit the longitudinal movement of the fastening members within the brackets, and other brackets secured to the back member between the first brackets having bendable side walls extending above the uppermost perforation of the vertical series and forming jaws, between which a magazine or magazines fastened by said members is adapted to be accommodated and embraced, the arrangement of said perforations and said jaws permitting the fastening of magazines of respectively different thicknesses and types of binding and the supporting of the magazines against turning movement in said other brackets.

FRANK H. CRUMP.
